UNITED STATES PATENT OFFICE.

WILLIAM M. MITCHELL, OF LOUISVILLE, KENTUCKY.

RAIL-ANCHOR.

1,338,148.

Specification of Letters Patent. Patented Apr. 27, 1920.

Application filed December 22, 1919. Serial No. 346,678.

To all whom it may concern:
Be it known that I, WILLIAM M. MITCHELL, a citizen of the United States, residing at Louisville, in the county of Jefferson and State of Kentucky, have invented certain new and useful Improvements in Rail-Anchors, of which I do declare the following to be a full, clear, and exact description, reference being had to the accompanying drawing, forming a part of this specification.

The invention consists in the features of novelty hereinafter described, illustrated in the accompanying drawing and particularly pointed out in the claims at the end of this specification.

Figure 1 is a view showing in vertical section a railway rail mounted upon a cross tie and showing in end elevation my improved rail anchor applied to the base of said rail. Fig. 2 is a view in horizontal section on lines 2—2 of Fig. 1. Fig. 3 is a view in horizontal section through the web of the rail, the base of the rail and the stop thereon being shown in plan. Fig. 4 is a view in vertical section on the line 4—4 of Fig. 3. Fig. 4^a is a view on lines 4^a—4^a of Fig. 2. Figs. 5 and 6 are views similar to Figs. 1 and 2 but showing a modified form 30 of the invention. Fig. 7 is a view similar to Fig. 3 but showing a modification. Fig. 8 is a view in vertical section on the line 8—8 of Fig. 7.

A designates a railway rail and B designates one of the cross ties on which the rail is mounted. My invention is shown as embodied in a one-piece rail anchor the general construction of which is set forth and claimed in an application filed by me of even date herewith. This anchor comprises a jaw formed of an upper member c and a lower member c', an abutment plate c³ and a plate c² extending downwardly from the inner edge of the member c' of the jaw and at right angles to the jaw member c' and the abutment member c³.

The base flange a of the rail A is formed upon its upper surface with one or more stops or seats a² that are preferably formed upon the upper surface of the base flange a of the rail by welding thereon a small body of metal, which can readily be done by several of the familiar welding processes now

commonly employed, such for example, as the familiar oxy-acetylene process.

Preferably, each of the stops a² has extensions a⁵ at the ends thereof between which is formed a recess to receive the end of a screw D that passes through a threaded hole formed in the upper member c of the anchor jaw. The screw D as shown is provided with a lock nut d to guard the screw against accidentally working loose. The head of the screw is preferably of polygonal shape to enable it to be easily turned by a wrench.

In applying my anchor to a railway rail, the jaw of the anchor is forced over the base flange of the rail until the anchor is in the position shown in Fig. 1, after which the screw D will be turned downwardly until its lower end passes behind the stop a² and enters the seat between the end extensions a⁵ of the stop, after which the lock nut d will be turned down to guard the screw against working loose. When the anchor has thus been applied to the rail, the screw, coöperating with the stop a², will hold the anchor in place upon the base flange of the rail and as the rail tends to creep, its gripping movement will be resisted by the engagement of the abutment portion of the anchor with the cross tie B. This will produce a slight rocking movement of the anchor, causing its jaws to firmly grip the base flange of the rail with what is known as a "shackle action" and securely hold the rail against creeping, being aided in this by the engagement of the screw D with the stop a².

If desired, the end of the upper member c of the anchor jaw nearest to the tie D may be bent downwardly (see Fig. 4^a) to form an edge or edges that will more effectively grip the outer face of the base flange of the rail when the anchor is rocked slightly under the tendency of the rail to creep.

In the form of the invention illustrated in Figs. 5 and 6 of the drawing, the upper member c of the anchor is provided with two screws D that pass through threaded holes formed in the upper member of the anchor jaw adjacent its ends, lock nuts d being employed upon both of these screws. When the anchor is thus provided with two screws D, the base flange a of the rail will be provided with two stops a² similar to

the stops hereinbefore described. Instead of providing the upper surface of the base flange of the rail with stops α^2 projecting upwardly therefrom, it is obvious that seats 5 or depressions (one or more) may be formed in the base flange of the rail to receive the lower ends of the screw or screws D.

Having thus described my invention, what I claim as new and desire to secure by Letters Patent is:—

1. A rail anchor comprising a jaw for engaging one of the base flanges of a rail, a set screw threaded through one of the jaw members and arranged to engage the 15 face of the rail flange to hold the anchor in position thereon, and a depending abutment adapted to engage the side of the tie and coöperate therewith to rock the anchor in a vertical plane and thereby force said 20 jaw into gripping engagement with the upper and lower faces of the rail flange.

2. A rail anchor comprising a short jaw adapted to be slipped laterally over one of the base flanges of a rail and having a 25 threaded hole and a set screw passing through said hole to engage the rail flange; an abutment depending from said jaw to engage the side of a cross tie, the end of the lower member of said jaw extending no 30 farther than the bearing face of said abutment, the lower member of said jaw and

said abutment being adapted to be passed beneath the rail when the latter rests upon the tie.

3. A rail anchor comprising a short jaw 35 adapted to be slipped laterally into engagement with one of the base flanges of a rail between the cross ties of the track, said jaw being provided with a threaded hole therein and with a set screw passing through 40 said hole, said jaw having a depending abutment arranged below the jaw to engage the side of a cross tie and to rock the anchor in a vertical plane and thereby force said jaw into gripping engagement with the upper and lower faces of the rail flange.

4. The combination with a railway rail having the upper face of its base flange provided with a seat to receive the end of a screw, of a rail anchor comprising a jaw 50 adapted to be slipped laterally over said base flange, the upper portion of said jaw being provided with a hole and a set screw passing through said hole to engage said seat and the lower portion of said jaw being 55 provided with a depending abutment to engage the side of a cross tie to rock the anchor in a vertical plane and thereby force said jaw into gripping engagement with the rail flange.

WILLIAM M. MITCHELL.
